UNITED STATES PATENT OFFICE.

CHARLES E. MYERS, OF ST. LOUIS, MISSOURI, ASSIGNOR TO MICHAEL J. GILL AND FERDINAND J. TILLMAN, BOTH OF ST. LOUIS, MISSOURI.

STAPLING MACHINE.

Application filed November 20, 1918. Serial No. 263,265.

To all whom it may concern:

Be it known that I, CHARLES E. MYERS, a citizen of the United States of America, and a resident of the city of St. Louis and State of Missouri, have invented certain new and useful Improvements in a Stapling Machine, of which the following is a specification.

The primary object of this invention is in providing improvements in a stapling machine to such an extent whereby the device can readily be used for sewing or securing leathers or heavy fabrics together, and is especially capable for resoling shoes.

Another object is to provide an improved stapling machine that is capable of driving and clinching staples in the soles of shoes, in which a greater flexibility of action will be given to the shoe soles during the wearing thereof.

A further object is in providing an improved staple feeding mechanism relative to feeding the staples from the receiving hopper to the hammer.

Other and further objects will appear in the specification and be specifically pointed out in the appended claims, reference being had to the accompanying drawings exemplifying the invention, and in which,

Figure 1 is a side elevation of this improved stapling machine.

Figure 2 is a plan view of Fig. 1.

Figure 3 is a rear view of Fig. 1.

Figure 4 is a vertical section taken on the line IV—IV of Fig. 1.

Figure 5 is a fragmentary side elevation of a portion of the forward part of the machine taken in the direction of the arrow 5, Fig. 2.

Figure 6 is an enlarged horizontal section taken on the line VI—VI of Fig. 1.

Figure 7 is a fragmentary vertical section taken on the line VII—VII of Fig. 2.

Figure 8 is an enlarged fragmentary elevation further illustrating the action of the staple releasing members shown in Fig. 7.

Figure 9 is a vertical section taken approximately on the line IX—IX of Fig. 7.

Figure 10 is an enlarged vertical section taken on the line X—X of Fig. 6.

Figure 11 is an enlarged transverse vertical section taken on the line XI—XI of Fig. 10.

Figure 12 is an enlarged front elevation

disclosing the staple receiving guideway 55 with the cover plate removed therefrom.

Figure 13 is a front elevation taken on the line XIII—XIII of Fig. 1.

Figure 14 is a vertical section taken on the line XIV—XIV of Fig. 13.

Figure 15 is a fragmentary sectional view of the feeding ratchet wheel.

Figure 16 is an enlarged view of one of the staples used in connection with this improved stapling machine.

Figure 17 is an enlarged end elevation of Fig. 16.

Figure 18 is an enlarged horizontal section of the staple taken on the line XVIII—XVIII of Fig. 16.

Figure 19 is a fragmentary section of a portion of a shoe sole, showing the arrangement of a row of staples after they have been driven therein.

Figure 20 is a horizontal section taken on the line XX—XX of Fig. 19.

Referring to the drawings 1 designates a base member having a pair of upwardly extending standards 2, said base member being secured to a supporting stand 3 by a bolt 4. Formed on each of the standards 2 adjacent their upper ends is a bearing 5, said bearings being for the support of a horizontally arranged power shaft 6, and mounted on one end of said shaft is a driven pulley 7 which may be driven from a motor or other source of power while the opposite end of said shaft is adapted to support a turning handle 8 as shown in dotted lines in Figs. 1 and 3.

Secured to said shaft 6 between the bearings 5 is a cam wheel 9, and formed in one of the side faces of said cam wheel is a triangular shaped cam-way 10, having cam roller dwells 11, the intermediate portion of said cam-way between the dwells forming a cam 12 having actuating portions 13.

Adapted to traverse the cam-way 10 is a roller 14 which is mounted at one end of a rocker arm 15, said rocker arm being intermediate pivoted at 16 between a pair of bearings 17, one of which is formed integral with the extending portion 18 of each of the standards 2. The opposite end of said rocker arm 15 is comprised of a pair of extending portions 19, and carried by each of said portions 19 is a hammer support 20, and secured to the extending ends of said supports

20 by screws 21 is a depending driver bar 22 which is preferably constructed of spring steel so as to be flexible.

5 Integrally formed with each of the extending portions 18 of the standards 2 is an upwardly extending side wall 23, and mounted between said side walls is a staple receiving hopper 24. Secured to the front end of the hopper 24 is a front plate 25, which 10 forms part of the forwardly extending portion 26, the upper surface of said portion 26 being inclined, forming an inclined track-way 27, said track-way 27 having a rearwardly extending portion 28 which extends 15 into the hopper 24.

Carried by the front end of the portion 26 is a guide block 29 having a staple receiving guide-way 30, said guide-way being in communication with the lower and front end of 20 the track-way 27, and having a cover plate 31 for closing said guide-way.

The lower end of the hammer 22 is reciprocally mounted in the guide-way 30, and secured to the cover plate 31 is a leaf 25 spring 32 having an inwardly extending portion 33 which extends through an opening 34 formed in said cover plate, said inwardly extending portion being below the hammer 22 when the hammer is in elevated position, 30 said portion 33 of said leaf spring also being below the inclined surface of the track 27, (see Fig. 10).

Formed on each side of the portion 26, adjacent its lower end is a horizontal guiding surface 35, and slidably mounted on each of said guiding surfaces is a gripping or holding member 36, the forward ends of said members, as designated at 37, adapted to enter the guideway 30 of the guide block 29. 40 These members 36 are tied together by the rivets 38, and there being an opening 39 formed in the portion 26 for the travel of said rivets and their respective spacer members during the reciprocation of the gripping 45 members 36.

Formed in one of the members 36 is a socket 40, and engaged in said socket is a rounded end 41 of a bell crank lever 42 which is pivoted at 43 to the portion 26, the 50 opposite end of said lever 42 being bifurcated as designated at 44, said bifurcated end of said lever being engaged by a pin 45 which is carried by one of the hammer supports 20.

Mounted on one side of the extending portion 26 is a spring actuated arresting lever 46, said lever being mounted on a transversely arranged bolt 47 which passes through the portion 26, and mounted on said bolt at the opposite side of said portion 60 26 is another spring actuated arresting lever 48. Each of these arresting levers 46 and 48 have an angularly bent portion 49 and 50 respectively.

Co-operable with the arresting lever 46 is 65 an actuating finger 51 which is carried by

the rocker arm 15, and co-operable with the arresting lever 48 is an abutting portion 52 which is carried by one of the hammer supporting portions 20 of the rocker arm 15 (see Fig. 5).

Secured to the front plate 25 is an inclined guiding plate 53 which holds the staples in sliding relation to the trackway 27, and prevents them from jumping off as they leave the hopper 24. Passing through 75 the hopper 24 is a transversely arranged shaft 54, and secured to said shaft is a staple lifting member 55, said member being comprised of a hub 56 to which a pair of square formed plates 57 are secured, and formed 80 in each of said plates adjacent the corners thereof, and in oppositely disposed positions, are staple gripping notches 58.

The extending portion 28 of the trackway 27 extends between the plates 57 of the staple 85 lifting member 55, as shown more clearly in Fig. 7, and there being a rearwardly inclined surface 59 formed on said portion 28, which at one end is within the arc of the circle travelled by the notches 58, whereas 90 the upper end of said inclined portion 59 is above the arc of the circle travelled by said notches. One end of the shaft 54 extends through the hopper 24, and mounted on said extending end of said shaft is a grooved pulley 60 which has a crossed endless belt 61 mounted thereover, said belt at its opposite end being mounted over a grooved pulley 62 which is secured to the power shaft 6. Extending upwardly from the rear of the 100 base 1 is a bracket 63, and pivoted to said bracket by the bolt 64 is a bearing 65, said bearing being for the support of one end of a feed shaft 66. Mounted on said shaft is a ratchet wheel 67 which carries a plurality 105 of spring actuated ratchet teeth 68.

Mounted on the hub 69 of the ratchet wheel is a lever 70, having a slot 71 formed therein, said lever also carrying a dog 72 which is adapted to engage the teeth 68 of the ratchet 110 wheel 67. Secured to the underside of one end of the rocker arm 15 adjacent the roller 14 carried thereby, is a rearwardly extending portion 73, having a depending portion 74 which carries a pin 75, said pin engaging the 115 slot 71 of the lever 70.

Secured to said rocker arm adjacent its roller carrying end is one end of a coil spring 76, having its opposite end secured at 77 to the rear wall of the hopper 24. The 120 shaft 66 extends approximately horizontal beneath the rocker arm 15, the forward end of said shaft being journaled in a bearing 78 which is pivotally supported at 79 to a movable support 80, which is mounted in a 125 casing 81, said casing being secured to the forward end of the base 1.

Centrally and transversely arranged in the casing 81 is a bolt 82, and turnably mounted on said bolt is a shifting plate 83, said plate 130

having a groove 84 formed therein, which is arranged eccentric with the bolt 82, said groove being for the reception of one end of a pin 85 which is carried by the movable 5 support 80.

Secured to the shaft 66 adjacent the bearing 68 is a knurled roller 86 having an annular groove 87, said groove being in vertical alinement beneath the lower end of the 10 guideway 30 of the guide-block 29.

Referring to Figs. 16 to 20, it is preferable to have the staples used in this improved stapling machine bevelled as designated at 88 at their puncturing ends, said bevelling 15 to be done on the outer sides of the legs 89 of the staple, and diagonally of the center line A, shown in Fig. 18, so that when the staple is driven into the material, the legs 89 thereof will deflect from a right line, and 20 be driven angularly and inwardly towards each other, and yet will pass one another without touching, as shown in Figs. 19 and 20, thereby securely sewing two or more pieces of material together.

25 In the operation of this improved stapling machine, a quantity of staples on the order of the one shown in Fig. 16, in which the legs thereof parallel one another are dumped into the hopper 24, and power is given to the 30 shaft 6, either by the crank handle 8 or motor power from the pulley 7. In the meantime a shoe to be soled is engaged and held with the sole lowermost and the extending edge of the welt and sole thereof is inserted be- 35 tween the guide block 29 and roller 86, and the handle 90, which is secured to the shifting plate 83 is moved upwardly, thereby clamping the sole between the roller 86 and the guide block 29.

40 During the rotation of the shaft 6, the staple lifting member 55 upon being re- 45 volved in the direction of the arrow shown in Fig. 7, will force one or more staples into each of the notches 58 thereof, and carry the staples upwardly until the staples are forced from their respective notches on to the inclined surface 59 of the trackway ex- 50 tension 28, and eventually on to the downwardly inclined trackway 27.

55 During the travel of staples down the trackway 27, and in straddling position thereof, the first staple in order will be engaged by the angular portion 50 of the arresting lever 48, and in the timing operation or actuation of the rocker arm 15 the lever 48 is moved from engagement with the trackway, thereby allowing the first staple in order to travel farther down the trackway where it is arrested by the track engaging 60 portion 49 of the arresting lever 46. The arresting lever 48 is then returned to its track engaging position, thereby crowding and holding the rearwardly arranged staples away from the staple which is first in order, 65 (see Fig. 8). The actuating finger 51 is then

70 moved by the rocker arm 15 until it engages and moves the arresting lever 46 from engagement with the trackway 27, thereby allowing the first staple to slide down to the end of the trackway and rest against the driver bar 22 as the lower portion of said hammer is still below the inclined staple passage-way 91 of the guide block 29.

75 The staple resting against the driver bar is then in position to immediately drop into the guideway 30 as soon as the driver bar has travelled above the passageway 91, the upward and downward reciprocation of said driver bar being caused by the rocking movement of the rocker arm 15 which is actuated by the camway 10 of the cam wheel 9.

80 As shown in Fig. 1, the roller carrying end of the rocker arm 15 has been forced downwardly, thereby elevating the opposite end of said rocker arm, in which the lower or 85 staple engaging end of the driver bar 22 will be moved above the passageway 91 of the guide block 29, thereby allowing the staple to drop into the guideway 30 where it will be engaged by the extending end 33 of 90 the leaf spring 32, and simultaneous therewith, the gripping members 36 will engage against the legs 89 of the staple, thereby holding it against the plate 31, (see Fig. 10).

95 The driver bar 22 is then moved downwardly and since the staple is now in the path of travel of the driver bar in the guideway 30, the staple will be forced from its spring held position down between the forward ends of the gripping members 36, and as the legs of the staples enter the leather of the shoe sole, the staple legs being guided thereto and held in a straight position by the gripping members 36, said gripping members are then moved rearwardly and out of 100 the way of the descending driver bar by the actuation of the bell crank 42, the staple engaging end of the driver bar traversing the guideway 30 to the bottom thereof, thereby forcing the staple into the sole leather of the 110 shoe.

115 In the descending or driving operation of the driver bar 22, the arresting lever 46 is again actuated by the finger 51, thereby allowing another staple to complete its travel down the trackway 27, where it will engage against and be held by the hammer until the driver bar is elevated by the return movement of the rocker arm 15, which return movement of the rocker arm will cause the 120 abutting portion 52 carried thereby to engage the arresting lever 48 so as to allow the next staple bearing thereagainst to ride against the arresting lever 46 so that it will be ready for a succeeding discharging operation after each staple driving operation of the driver bar 22. As the driver bar is moved upwardly, the depending portions 74 and pin 75 carried thereby will force the lever 70 downwardly, thereby causing the 130

dog 72 carried by said lever 70 to bear on an adjacent tooth 68 of the ratchet wheel 67, thereby actuating the ratchet wheel 67 and incidentally rotating the feed roller 87, and 5 inasmuch as the surface of said roller is in engagement with the underside of the shoe sole, the shoe sole will be moved to a position ready to receive the next staple.

From the aforesaid operation it is to be 10 noted that the movement of the rocker arm 15 actuates all of the parts relating to the discharge of the staples from the trackway 27, the guiding and driving of the staples through the guide block and the feeding 15 over of the shoe sole, thereby providing for a simple and inexpensive construction of a stapling or nailing machine.

After a shoe has been soled with this improved machine, the staples contained therein will be clinched as before described, and 20 as shown in Figs. 19 and 20, thereby providing a secure fastening means which will be susceptible to any desired amount of flexibility as regards good wearing qualities of 25 a shoe sole which is constructed or repaired in the manner described, as the inclining clinching positions of the staple legs will afford and allow the natural suppleness of a shoe sole as against the ordinary type of 30 nailed sole, in which the nails are vertically arranged in the sole. Furthermore, the points of the staple legs are driven downward in a shoe sole as against the upward driving of shoe nails.

35 What I claim is:

1. A stapling machine comprising a staple receiving hopper, an inclined trackway leading from said hopper, a rocker arm, a staple arresting member co-operable with said 40 trackway and actuated by said arm, a driver bar located at the opposite end of said trackway and secured to said arm and a work feeding mechanism located beneath said driver operated by said arm.

45 2. A stapling machine comprising a staple receiving hopper, an inclined trackway leading from said hopper, a rocker arm, a driver bar located at the opposite end of said trackway and secured to said arm, and a work 50 feeding mechanism located beneath said driver operated by said arm.

3. A stapling machine comprising a staple receiving hopper, an inclined trackway lead-

ing from said hopper, a rocker arm, a driver bar located at the opposite end of said trackway secured to said arm at one end, and a work feeding mechanism located beneath said driver bar and operated by the actuation of the opposite end of said arm. 55

4. A stapling machine comprising a staple 60 receiving hopper, an inclined trackway leading from said hopper a rocker arm, a staple arresting means co-operable with said trackway and said arm, a reciprocally mounted driver bar located at the lower end of said 65 trackway, and a work feeding mechanism located beneath said driver bar and intermittently operated by said arm.

5. A stapling machine comprising a staple 70 receiving hopper, an inclined trackway leading from said hopper, a guideway located adjacent the lower end of said trackway, means for lifting staples from said hopper to said trackway, a rocker arm co-operable at one end with a revolving cam staple arresting members co-operable with said trackway to be actuated by said arm, and a driving bar secured at the opposite end of said arm reciprocally mounted in said guideway. 75

6. A stapling machine comprising a staple 80 receiving hopper, an inclined trackway leading from said hopper, a rocker arm carrying a driver bar located at the opposite end of said trackway, revoluble work feeding means beneath the driver bar and means to operate 85 said work feeding means from said rocker arm.

7. In a stapling machine, a staple receiving guideway, means located within said guideway for holding a staple therein, a 90 rocker arm bearing a driver bar, said bar being reciprocal in said guideway, and a reciprocal holding member actuated by said arm adapted to bear against the staple during the initial driving movement of said bar. 95

8. In a stapling machine, a staple receiving guideway, a staple conveying means leading to said guideway, a rocker arm bearing a driver bar, a staple arresting member co-operable with said conveying means and actuated by said arm, and a reciprocal holding member operated by said arm adapted to guide the staple in said guideway during the initial driving movement of said bar. 100

CHARLES E. MYERS.
